UNITED STATES PATENT OFFICE.

WILLIAM ALEXANDER MOORE, OF SHERMAN, TEXAS.

PRESSURE DEVICE.

SPECIFICATION forming part of Letters Patent No. 284,044, dated August 28, 1883.

Application filed May 19, 1883. (No model.)

To all whom it may concern:

Be it known that I, WILLIAM A. MOORE, a citizen of the United States, and a resident at Sherman, in the county of Grayson and State of Texas, have invented certain new and useful Improvements in Pressure Devices; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and shows a front view of the device inside of a half-barrel, shown in section. Fig. 2 is a perspective view. Figs. 3, 4, 5, 6, and 7 are detail views of the different parts.

This invention has relation to portable pressure devices for use in casks, boxes, barrels, or other receptacles; and the invention consists in the construction and novel arrangement of the pointed dogs and cam-levers pivoted together, and in the combination therewith of a pivot-bolt having its nut secured by means of a locking-key, all as hereinafter set forth.

In the accompanying drawings, the letters *a* and *b* designate two dogs, having pointed outer ends, *v*, and being connected together by a pivot-bolt, *c*, at their lower ends. This pivot-bolt also connects the cam-levers *d* and *e*, the bolt passing through said levers near their convex edges *g*. In order that the bolt shall remain securely in position, notwithstanding the working of the cam-levers and dogs, it is arranged with a locking-key, *h*, which engages the bolt and nut *k*. The bolt *c* is formed with a longitudinal groove or key-seat, *l*, of such depth that the wire or key *h*, when placed in the groove, will not interfere with the thread of the nut when the lat-

ter is turned on the bolt. The nut is also grooved transversely in its face, as indicated at *m*, in order that the wire or key may be drawn into the groove, and thereby lock the nut on the bolt.

The pressure device is operated by adjusting the pointed ends *v* of the dogs outward, so that they will engage the side walls of the box or barrel or other receptacle containing the material to be put under pressure. The cam-levers, which are pivoted to the dogs, are at first arranged in horizontal or nearly horizontal position. In order to apply the pressure on the follower *f*, the handles of the cam-levers are raised and brought toward each other, so that through the purchase obtained by the dogs the cam-edges *g* of the levers are brought to bear, forcing the follower downward.

This pressure device is designed to serve various useful purposes in connection with barrels, boxes, and other common receptacles, as it enables articles placed therein to be packed in small space or held down under brine or other liquid.

Having described this invention, what I claim, and desire to secure by Letters Patent, is—

1. A pressure device consisting of the pointed dogs *a* *b* and the cam-levers *d* and *e*, pivoted together, and adapted to be used inside of a barrel or other receptacle, substantially as specified.
2. The combination, with the pointed dogs *a* *b* and the cam-levers *d* *e*, of the grooved bolt *c*, grooved nut *k*, and the key or locking-wire *h*, substantially as specified.

In testimony whereof I affix my signature in presence of two witnesses.

WILLIAM ALEXANDER MOORE.
